FIG. 3

FIG. 4

FIG. 1 is a top plan view of a ceiling tile or similar article showing the new design of my invention.

FIGS. 2 through 4 are top plan views of a ceiling tile or similar article wherein each of said figures shows a modified form of the new design of my invention.

FIG. 5 is an edge view of a ceiling tile or similar article.

Certain of the stippled areas of the design are areas where small light reflecting colored particles are adhered to a lighter background, in particular, the arrangement wherein gold colored particles are adhered to a white background is preferred.

I claim:

The ornamental design for a ceiling tile or similar article, substantially as shown and described.
